UNITED STATES PATENT OFFICE

LOUIS COURTOT, OF PARIS, FRANCE, ASSIGNOR TO AMERICAN RADIATOR COMPANY, OF NEW YORK, N. Y., A CORPORATION OF NEW JERSEY

LOW-PRESSURE BOILER

Application filed March 24, 1926, Serial No. 96,941, and in France March 25, 1925.

My invention has for its object to provide a low pressure boiler of small size for a given output and in which the heat is utilized in the best conditions.

To this effect the said boiler, whereof the main body consists of tubular panels providing for water circulation, comprises on at least one of its sides, flues or channels for the evacuation of smoke which flues or channels are formed by two sets of tubular panels having the parallel position and by two general collecting conduits which are connected with the particular collecting conduits of the said panels and are horizontally disposed above and below the said channels. The latter may be provided with one or more intermediate partitions as baffles for the circulation of the smoke whereby the heat of combustion will be properly utilized.

The roof of the boiler furnace consists of firebrick or like refractory material in order to provide for the complete combustion of the gas distilled by the combustion which might ascend into the upper part of the furnace without being ignited. In the said furnace roof is preferably disposed a metal conduit which serves as a support for the firebrick elements and also to introduce into the combustion chamber a supply of air which has been heated by contact with the walls of the boiler in order to aid in the complete combustion of the said distilled gas.

The appended drawings show by way of example a constructional form of boiler according to my said invention.

Fig. 1 is a side elevation of the boiler, with parts in section on the lines A—A and B—B, and with parts broken away according to the line C—C of Fig. 2.

Fig. 2 is a half plan view and a half horizontal section.

Fig. 3 is a half rear elevation and a half cross section of the boiler.

The boiler herein represented has a rectangular shape, and its two lateral faces are each constituted by two parallel rows of tubular panels 1, each row comprising five panels, as shown in Fig. 2, this number is variable with the capacity of the boiler which is to be constructed. Each panel comprises a plu-

rality of vertical channels which are separated by solid parts and are connected together by an upper collecting conduit 2 and a lower collecting conduit 3.

The front and rear faces also consist of panels of the same kind which are disposed in single rows; in the front face is provided a loading door 4 and an ash pit door 5. The rear face comprises the lateral apertures connecting the channels formed between the panels 1 with a smoke box 8; the latter is provided with a conduit 6 for connection with the stack and is fitted with a damper 7 as well as with doors for regulating the draft and for cleaning purposes, not shown.

The upper collecting conduits 2 and the lower collecting conduits 3 of the panels 1 are connected together and to the general collecting conduits 9 and 10 which are disposed between the same at the upper and lower part of the said channels. In like manner, the upper and lower collecting conduits at the front and rear communicate with the ends of the general collecting conduits 9 and 10, for instance as shown at the lower part of Fig. 1.

The two lower general collectors 10 are connected together by a conduit 11 supplying the return water of the plant; the two upper collectors 9 are in like manner connected together by a conduit 12 provided with a neck 13 which is connected to the hot water discharge conduit. Instead of being placed at the front as shown, the conduit 12 may be disposed upon the top of the boiler, the connection being made directly with the general collectors 9.

The panels of the inner rows on the sides of the boiler have at the top the apertures 14 (two per panel) serving to connect the combustion chamber of the boiler, situated above the grate 15, with the interior of the said channels. Each of the channels is provided with a horizontal partition 16 which serves as a baffle for the circulation of the gas; above the said partition the gas circulates forwardly, then to the lower part, and rearwardly, and proceeds into the stack 6 through the box 8.

The roof or crown member of the boiler furnace consists of elements made of fire-

brick, asbestos composition, or the like, shown at 17, and on the axis of the said roof is disposed the metallic conduit 18 whose ends are secured to the front and rear panels of the boiler. At the rear of the conduit 18 is the discharge end of an air supply conduit 19 which is disposed against the rear end of the boiler; in the bottom of said conduit 18 are apertures 20 through which the air—
10 preliminarily heated by circulating in contact with the rear panel and with the walls of the conduit 18—enters the said combustion chamber.

It should be observed that due to the position of the apertures 14 near the highly heated furnace roof 17 the gas is raised to a very high temperature at the instant when it is about to enter the said channels, so that the complete combustion of the gas will be insured.
15

For the air circulation conduit 18 aiding in the combustion, I may substitute a tube or like hollow member affording a water circulation which is connected at its ends with 25 the front and rear panels, or otherwise, a simple solid cross-piece supporting the refractory elements 17 should they be shorter than the width of the boiler.

From the preceding considerations, it will 30 be observed that a boiler thus constructed will offer the following advantages:

By reason of the small size and light weight of the constructive parts of the boiler, the construction, erection and transportation of 35 the boiler may be carried out with great facility.

Due to the disposition of the tubular panels on both sides of the channels, the boiler will possess a large heat-transmitting surface.
40

Relatively to its size, the boiler possesses a large grate surface and a large fuel capacity.

The apparatus occupies a small space for a given output.

45 The water circulation is effected at a more rapid rate than in the known low pressure boilers.

The combustion of the gas is complete, due to the refractory roof of the furnace and to 50 the arrangement of the conduit 18 and the channel apertures 14; the reduction in the heating surface corresponding to the presence of the said roof is amply compensated by the improved combustion, which is completed in the said channels.

Obviously, the said invention is not limited to the constructional form which is herein-before described by way of example; for instance the number of channels is optional, and 55 each may comprise a suitable number of partitions 16 offering an increased path for the gas before its evacuation.

Should the said boiler be employed for producing low pressure steam, a receptacle serv-

ing as a steam drum should be disposed above the same.

Having thus described my apparatus, what I claim as new therein, and my own invention, is:

1. A boiler of the character described comprising a plurality of vertical fluid-containing panels forming the walls of the boiler, a crown member, and a duct disposed longitudinally of the boiler at the top thereof and serving to supply secondary air to the interior of the boiler, said duct and said panels serving to support said crown member, substantially as specified.
70

2. A boiler of the character described comprising a plurality of vertical fluid-containing panels forming the fuel receptacle, and flues laterally thereof, a duct for supplying secondary air to said fuel receptacle disposed longitudinally of the boiler at the top thereof, a crown member of refractory material supported by said panels and said duct, certain of said panels having openings adjacent to said crown member to provide outlets from said fuel receptacle to said flues, substantially as specified.
85

3. A boiler of the character described comprising a plurality of longitudinally and transversely extending vertical fluid-containing panels forming the fuel receptacle, a plurality of longitudinally extending vertical fluid-containing panels disposed in spaced relation to said first-named longitudinally extending panels, headers disposed at the upper and lower ends of said spaced panels 95 communicating therewith and forming there-with enclosed longitudinal flues at the opposite sides of the boiler, a longitudinal secondary air duct disposed centrally longitudinally of the boiler at the top thereof, a 100 crown member at the top of the boiler composed of elements of refractory material supported by said panels and said duct, the inner of said longitudinal panels having openings therein adjacent to said crown member to provide outlets from said fuel receptacle to said flues, substantially as specified.
105

In testimony whereof I have hereunto affixed my signature.

LOUIS COURTOT.
